HEIGHT INDICATING SLIDE

Samuel George Zuckerman, Brooklyn, N.Y.

Application February 11, 1959, Serial No. 54,561

Term of patent 7 years

(Cl. D52—1)

Fig. 1 is an elevational view of a height indicating slide, showing my new design. The portion broken away represents indeterminate length.

Fig. 2 is a plan view thereof.

The rear side of the article depicted in Fig. 1 is like the side depicted in said figure but is an opposite plan view thereof.

I claim:

The ornamental design for a height indicating slide, as shown and described.
